UNITED STATES PATENT OFFICE.

NICOLAI H. HILLER, OF CARBONDALE, PENNSYLVANIA.

CONDENSER AND METHOD OF CONDENSATION.

1,360,748.

Specification of Letters Patent. Patented Nov. 30, 1920.

Application filed July 9, 1915. Serial No. 38,851.

To all whom it may concern:

Be it known that I, NICOLAI H. HILLER, a citizen of the United States of America, and a resident of Carbondale, in the county of 5 Lackawanna and State of Pennsylvania, have invented certain new and useful Improvements in Condensers and Methods of Condensation, of which the following is a specification.

10 My invention relates to improvements in condensers, particularly condensers designed for use in refrigeration apparatus, including ice making plants, and to processes of condensation. The improved condenser herein described is particularly intended for condensing ammonia; though I do not limit it to any particular use. In its more usual form, it is a coil condenser of the up-flow type and comprises means for the 15 return to the gas-inlet of a portion of the condensate, the fluid circulating through the condenser being a mixture of the previously condensed liquid with the gas to be condensed and liquid formed by condensation of such gas. My invention consists in various features of construction and arrangement whereby the efficiency of the condenser is very greatly increased, and whereby it is rendered very steady in operation; and in the novel process of condensation carried out in the apparatus.

20 The objects of my invention are, to obtain greater condensing capacity per unit of cooling surface than has been obtainable heretofore; to avoid surging and similar disturbances such as have been encountered frequently in other types of coil condensers; and to provide a condenser which, while 25 simple in construction and easy to operate, is compact and highly efficient.

30 I will now proceed to describe my invention with reference to the accompanying drawings, and will then point out the novel features in claims:

35 Figure 1 shows a side elevation of one type of condenser embodying my invention.

40 Fig. 2 shows a fragmentary end view of a plurality of condenser units constructed in accordance with my invention.

45 Fig. 3 shows, on a larger scale than the previous views, a central vertical section of the type of injector employed in connection with the condenser.

50 Fig. 4 is a transverse vertical section on a larger scale than the previous views, of the upper portion of the condenser show-

ing the sprinkling trough and splash plates; and

55 Fig. 5 is a fragmentary side elevation of the upper portion of the condenser, showing the sprinkling trough and splash plates.

Fig. 6 is a side elevation of an alternative form of condenser;

60 Fig. 7 is a fragmentary vertical section, on a larger scale, of a portion of the condenser of Fig. 6;

65 Fig. 8 is a fragmentary horizontal section of the condenser of Fig. 6 showing the injector through which the circulating pipe is connected to the bottom run of the condensing coil.

70 Fig. 9 shows a transverse section through one of the double pipe-runs of the condenser shown in Fig. 6.

75 Referring first to Fig. 1: Numeral 1 designates a return-bend pipe coil conduit consisting of a plurality of horizontal or nearly horizontal lengths or runs connected by return-bends. 2 designates the inlet to this pipe coil, 1, such inlet being located at the bottom thereof, and 3 designates the outlet of such pipe coil 1.

80 Beneath the pipe coil, 1, there is another coil 4, of the general nature of the coil 1 above, but the principal function of which coil 4 is to cool the gas to be condensed. The gas to be condensed is received through a header 5 and valve 6, and is passed first, through the preliminary cooling coils 4, and thence through an injector 7, shown in section in Fig. 3,

85 into the inlet 2 of the main condenser coil 1. A portion of the condensate is delivered from the outlet 3 of coil 1, through a return-flow circulation pipe 8 having in it a U-trap 9 dropping well below the inlet 2, to the combining space 10 of the injector. The gas to be condensed passes through a nozzle 11

90 of this injector into the inlet 2 and draws with it condensate from this combining space, the fluid entering the inlet 2 from injector 7, being a mixture of gas and of liquid condensate. The coils 1 are cooled by means of water or other suitable cooling fluid supplied from a sprinkling trough 12, which cooling water drips over the pipes of coil 1, from pipe to pipe, and then drips over the pipes of coil 4. The mixture of liquid and gas, entering coil 1 through inlet 2, flows through the first horizontal run of the condenser of coil 1, and then back through the second run of that coil, and forward through the third run of that coil, and

100

105

110

so on upward, the proportion of condensate in such mixture continually increasing owing to the condensation due to the cooling action of the water flowing over the coils.

5 I have found it desirable to provide, at various intermediate parts of the coil 1, drip pipes 13 leading to a condensation header 14; and to such header I connect a condensate outlet header 15, through a valve 16. 10 In the operation of this condenser, gas entering at 5 is cooled by passage through the lower pipe coil 4, and thence passes through the injector nozzle 11, drawing liquid condensate from the pipe 8 and outlet 15 3 of the condenser, and then flowing, mixed with the liquid condensate from return pipe 8, into the lower run of the main condensing coil 1, and thence flowing upward through the several runs of coil 1, being continually 20 condensed by the cooling action of the cooling water flowing over coil 1. In order to draw off a portion of the liquid condensate from different portions of the condenser, and thereby to reduce the percentage of liquid 25 to gas, and also to reduce any possible tendency to surging in the condenser, the drip connections 13 are provided; through which drip connections a portion of the liquid condensed will be drawn off into the 30 header 14, and thence delivered into condensation outlet 15.

The pressure in the condensing coils is highest at the bottom and grows progressively lower toward the top, due to friction 35 in the coil and decreasing hydrostatic head. In the drip connections 13 the liquid lies at different levels depending upon the relative pressures of the portions of the condenser to which these drip connections are connected; for example, the liquid will lie lower in the first pipe 13 (the one having the lowest connection to the condenser) than it will in the next pipe 13, and so on, the final level 40 of the liquid being determined by the overflow pipe 18 in header 14. Since the liquid acted upon exists as liquid in these drip pipes 13, these pipes 13 constitute traps, preventing short circuiting of the gas from the first pipe 13 through the header 14 direct to 45 the outlet 16.

In practice it has been found that these drip pipes very materially affect the performance of the condenser. In experiments, the drip pipes have been closed off by valves 55 provided in them, and it has been found that the head pressure of the condenser is materially higher than if those drip pipes be open. On the other hand, there seems to be no occasion for the provision of drip 60 pipes lower down in the condenser than shown, because when this was tried the pressure went up, possibly due to backing up of liquid.

The trapped drip pipes 13 greatly facilitate 65 the drawing off of air and foul gas

(gas which does not condense readily) from the condenser through the valve 17, or down through the drip header 14, valve 16, and thence to the anhydrous receiver. In certain old types of condensers attempts were 70 made to draw off foul gas from the top of the condenser through the anhydrous receiver, and it was found that if this were attempted, the gas to be condensed in runs other than the top run of the condenser, 75 would also be drawn off through the anhydrous receiver. But in my condenser, since the drip pipes 13 are trapped, gas can be drawn off from the top run without drawing off gas from the lower runs, except as 80 that gas first passes up through the condenser into the top run.

The trap 9 in circulating or return-flow pipe 8 I have found to be very important. In experiments, I have used such a return pipe without the trap or its equivalent, and it was found that, without use of the trap or its equivalent, the return of condensed liquid through the pipe 8 would soon cease, and that pipe 8 would grow warm, showing 90 that gas was flowing back through the pipe 8 instead of the condensed liquid flowing down through that pipe; in other words, there is a tendency for the gas to short circuit the condenser, through pipe 8, if the trap 9 or its equivalent be not employed. As indicated in Fig. 2, in practice there may be a plurality of these coils 1 and 4 connected to a common gas supply header 5 and an anhydrous outlet header 15, each pipe coil 1-4 100 having its own return pipe 8 and injector 7, and, of course, having its own drip pipes 13.

The overflow pipe 18 within drip header 14 is provided, near the bottom of such header, with an opening 19, so that, when the condenser is to be drained, the liquid can be drawn off through valve 16 clear 105 down to this opening 19.

The sprinkler trough 12 is of usual construction. Because of the high efficiency 110 of this condenser, and because of its consequent high condensing capacity, a rather greater flow of cooling water is maintained from trough 12 than has been common in the past, in connection with coil condensers, and therefore I have found it important to provide splash plates 21, beneath trough 12, which splash plates confined the cooling 115 water to the condensing coils.

The efficiency of this condenser has proved 120 to be very high. One such condenser, having about 150 square feet of cooling surface, and operated with cooling water at a temperature of about 60 degrees Fahrenheit, 125 showed refrigerating capacity of 29 tons, with a head pressure of 125.7 pounds, the temperature of the anhydrous ammonia leaving the condenser being 73.8 degrees Fahrenheit; the cooling water used being 66.9 gallons per minute, and being 2.30 per 130

minute per ton of refrigeration. This represents an increase of 4.1 tons refrigerating capacity (16½%) over the best performance of any other condenser of like surface known to me, with a smaller consumption of cooling water per ton of refrigeration capacity than in any other condenser known to me.

The high observed efficiency of this condenser is due in large measure to the fact that in the lower runs of the condenser there is present a large proportion of cooled liquid (derived from return pipe 8) in mixture with the gas, so that there is a high rate of transmission of heat from such mixture to the walls of the condensing conduit; also to the fact that higher up in the condenser, where the proportion of liquid to gas is increased greatly as a result of condensation of the gas, a considerable proportion at least of the liquid is drawn off, so restoring a proper proportion of liquid to gas in the mixture which passes up beyond such draw-off points.

In Figs. 6, 7 and 8 I illustrate an alternative form of condenser, in which, instead of flowing cooling water over the condensing coils, I flow cooling fluid through pipes located within the cooling coils. In these figures, numeral 1^a designates a return bend pipe conduit similar to the return-bend pipe conduit 1, of Fig. 1, except that the pipe conduit 1^a has within it an interior pipe conduit 12^a for the flow of cooling water; the pipes 12^a being extended out through the ends of the return-bend pipe fittings of the conduit 1^a, and being connected outside of such return-bend pipe fittings, by other return-bend pipe fittings 12^b. These pipes 12^a are provided with spiral ribs 12^c (see particularly Fig. 7) which substantially fill the annular space between pipes 1^a and 12^a, forcing the fluid being condensed to flow helically around pipes 12^a; whereby a very efficient cooling action by these pipes 12^a is secured. A circulating connection 8 is provided, as in Fig. 1, for the return of a portion of the condensate through the trap 9 to the lower run of the condenser. The condenser comprises, as in Fig. 1, two pre-cooling runs 4. As in Fig. 1, a condensation header 14 is provided, together with drip connections 13 to various levels of the condenser. The operation of the condenser is obviously the same as that of the condenser shown in Fig. 1.

I do not limit myself to the use of a U-trap 9 as means for preventing short-circuiting of the gas to be condensed, with respect to the condenser. Equivalents for that U-trap may be employed; a very sensitive check valve would be such an equivalent, but that check valve would have to be very sensitive indeed.

This application is in part a continuation

of my application filed January 11, 1913, Serial No. 741,576.

The drip outlet is not claimed specifically herein, but is made the subject matter of a separate co-pending application, Serial No. 70 413,286, filed September 28th, 1920.

What I claim is:

1. An upflow condenser such as described comprising a conduit having an inlet and an outlet, the latter at a higher level than the former, such conduit forming a continuous passage for gas to be condensed from such inlet upward to said outlet, a main liquid drawoff separate from said outlet, means for flowing cooling medium in heat exchanging proximity to such conduit, means, comprising a return conduit having means for preventing back flow of gas, for returning a portion of the liquid condensate of such condenser from said outlet to the lower portion of such condenser, and means for admitting gas to be condensed to the lower portion of such condenser.

2. An upflow condenser such as described, comprising a conduit having an inlet and an outlet, the latter at a higher level than the former, such conduit forming a continuous passage for gas to be condensed from such inlet upward to said outlet, means for flowing cooling medium in heat exchanging proximity to such conduit, means, comprising a return conduit having a trap for preventing back flow of gas, for returning a portion of the liquid condensate of such condenser to the lower portion of such condenser at a point above said gas inlet, and means for admitting gas to be condensed to the lower portion of such condenser.

3. An upflow condenser such as described comprising a plurality of conduits each having an inlet and an outlet, the latter at a higher level than the former, each conduit forming a continuous passage for gas to be condensed from its inlet upward to its outlet, means for flowing cooling medium in heat exchanging proximity to such conduits, and means, comprising a plurality of return conduits each having a trap-loop extending below the said inlet of the condenser, for returning a portion of the liquid condensate of each condenser conduit to the lower portion of the same condenser conduit.

4. A condenser such as described comprising a conduit having an inlet and an outlet, the latter at a higher level than the former, such conduit forming a continuous passage for gas to be condensed from such inlet upward to said outlet, means for flowing cooling medium in heat exchanging proximity to such conduit, means, comprising a return conduit having means for preventing back flow of gas, for returning a portion of the liquid condensate of such condenser to the lower portion of such condenser, and means for admitting gas to be

condensed to the lower portion of such condenser, comprising an injector connected also to said return conduit, and arranged to mingle the returned condensate with the entering gas.

5. A condenser such as described comprising a return-bend pipe conduit having substantially horizontal runs connected by return-bends and having an inlet and an outlet, the latter at a higher level than the former, such conduit forming a continuous passage for gas to be condensed from such inlet upward to said outlet, means for flowing cooling medium in heat exchanging proximity to such conduit, means, comprising a return conduit having means for preventing back flow of gas, for returning a portion of the liquid condensate of such condenser to the lower portion of said condenser, and means for injecting gas to be condensed into one of the substantially horizontal runs of such condenser coil and thence upwardly through that coil to the outlet thereof.

6. An upflow condenser such as described comprising a return-bend pipe conduit having substantially horizontal runs connected by return-bends and having an inlet and an outlet, the latter at a higher level than the former, such conduit forming a continuous passage for gas to be condensed from such inlet upward to said outlet, means for flowing cooling medium in heat exchanging proximity to such conduit, means for injecting gas to be condensed into one of the lower horizontal runs of such conduit, and thence upward through the return-bend conduit to the outlet thereof, a return conduit arranged to return a portion of the liquid condensed from the upper portion of such condenser coil to the lower portion thereof, and means independent of said return conduit for taking off condensed liquid directly from an intermediate portion of such coil.

7. A condenser such as described comprising a conduit having an inlet and an outlet, the latter at a higher level than the former, such conduit forming a continuous passage for gas to be condensed from such inlet upward to said outlet, means for flowing cooling medium in heat exchanging proximity to such conduit, a return conduit for returning a portion of the liquid condensate of such condenser to the lower portion of such condenser, means for admitting gas to be condensed to the lower portion of such condenser, and trapped draw off connections connected to the condenser at different levels, for drawing off a portion of the liquid condensed.

8. An upflow condenser such as described comprising a conduit having an inlet and an outlet, the latter at a higher level than the former, such conduit forming a continuous passage for gas to be condensed from such inlet upward to said outlet, means for flowing

cooling medium in heat exchanging proximity to such conduit, a return conduit for returning a portion of the liquid condensate of such condenser to the lower portion of such condenser, means for admitting gas to be condensed to the lower portion of such condenser, a drip header, and drip connections connected to said header independent of said return conduit for drawing off a portion of the liquid condensed directly from said condenser conduit.

9. A condenser such as described comprising a conduit having an inlet and an outlet, the latter at a higher level than the former, such conduit forming a continuous passage for gas to be condensed from such inlet upward to said outlet, means for flowing cooling medium in heat exchanging proximity to such conduit, a return conduit for returning a portion of the liquid condensate of such condenser to the lower portion of such condenser, such return conduit having means for preventing back flow of the gas, means for admitting gas to be condensed to the lower portion of such condenser, and trapped draw off connections connected to the condenser at different levels, for drawing off a portion of the liquid condensed.

10. An upflow condenser such as described comprising a conduit having an inlet and an outlet, the latter at a higher level than the former, such conduit forming a continuous passage for gas to be condensed from such inlet upward to said outlet, means for flowing cooling medium in heat exchanging proximity to such conduit, a return conduit for returning a portion of the liquid condensate of such condenser to the lower portion of such condenser, such return conduit having means for preventing back flow of the gas, means for admitting gas to be condensed to the lower portion of such condenser, a drip header, and drip connections therefrom to said conduit intermediate of its ends for drawing off a portion of the liquid condensed from the upflowing gas.

11. An upflow condenser such as described, comprising a double-pipe coil comprising inner and outer pipes, one of which is arranged for the flow of cooling fluid, the other having an inlet and an outlet, the latter at a higher level than the former, the inlet adapted for the entry of gas to be condensed, a return conduit for returning a portion of the liquid condensate of such condenser from said outlet to said gas inlet and means for drawing off a portion of the condensed liquid from a point intermediate of the ends of the coil.

12. A condenser such as described comprising a double-pipe coil comprising inner and outer pipes, one of which is arranged

for the flow of cooling fluid, the other having an inlet and an outlet, the latter at a higher level than the former, the inlet adapted for the entry of gas to be condensed, 5 and a return conduit for returning a portion of the liquid condensate of such condenser to said gas inlet, and trapped draw off connections connected to the condensing space of such condenser at different levels for 10 drawing off a portion of the liquid to be condensed.

13. A condenser such as described comprising a double-pipe coil, having inner and outer pipes, the former adapted for the flow 15 of cooling fluid, the latter having inlet and outlet connections to the annular space between the inner and outer pipes, the outlet at a higher level than the inlet, such inlet adapted for the entry of gas to be condensed, a return conduit arranged to return 20 a portion of the liquid condensate from the upper portion of such annular space to the said gas inlet and a separate draw-off for another portion of the liquid condensate.

25 14. A condenser such as described comprising a double-pipe coil, having inner and outer pipes, the former adapted for the flow of cooling fluid, the latter having inlet and outlet connections to the annular space 30 between the inner and outer pipes, the outlet at a higher level than the inlet, such inlet adapted for the entry of gas to be condensed, a return conduit arranged to return a portion of the liquid condensate from 35 the upper portion of such annular space to the said gas inlet, said return conduit provided with means for preventing back flow of gas and said coil having a liquid draw-off below said outlet.

40 15. A condenser such as described comprising a double-pipe coil, having inner and outer pipes, the former adapted for the flow of cooling fluid, the latter having inlet and outlet connections to the annular space 45 between the inner and outer pipes, the outlet at a higher level than the inlet, such inlet adapted for the entry of gas to be condensed, a return conduit arranged to return a portion of the liquid condensate from 50 the upper portion of such annular space to the said gas inlet, and trapped draw off connections connected to said annular space at different levels, for drawing off a portion of the liquid condensed.

55 16. A condenser such as described comprising a double-pipe coil, having inner and outer pipes, the former adapted for the flow of cooling fluid, the latter having inlet and outlet connections to the annular space 60 between the inner and outer pipes, the outlet at a higher level than the inlet, such inlet adapted for the entry of gas to be condensed, means for drawing off a portion of

the condensate at a point intermediate of the end of the coil, a return conduit arranged to return a portion of the liquid condensate from the upper portion of such annular space to the said gas inlet, and a helical rib within such annular space converting such space into a helical passage. 70

17. An upflow condenser such as described comprising a return bend pipe conduit consisting of substantially horizontal runs connected by return bends, such return bends being relatively short as compared with the 75 length of the horizontal runs, such conduit having an inlet and an outlet, the latter at a higher level than the former, means for flowing a cooling medium in heat exchanging proximity to such conduit, means for 80 mixing gas to be condensed with a portion of the liquid already condensed, and for discharging such mixture by the action of the gas through the inlet of such conduit above the lowermost part of the condenser 85 directly into a horizontal run of the conduit and thence upward through the conduit, and a permanently open connection for delivering a portion of the liquid condensed to such mixing means. 90

18. The herein described method of condensation, which comprises mixing a gas to be condensed with the liquid product of previous condensation, flowing such mixture in heat exchanging relation to, but out 95 of contact with, a heat absorbing medium of lower temperature than such mixture, and thereby causing condensation of the gas so mixed with the said liquid, and at a plurality of spaced points in the progress 100 of the mixture withdrawing therefrom a portion of the liquid of the mixture, and thereby restoring a desirable proportion of liquid to gas in such mixture.

19. The herein described method of condensation, which comprises mixing a gas to be condensed with a liquid, flowing such mixture in heat exchanging relation to, but out of contact with, a heat absorbing medium of lower temperature than such 110 mixture, and thereby causing condensation of the gas so mixed with the said liquid, and at a point in the progress of the mixture intermediate of the ends of its cooled path withdrawing therefrom a portion of the 115 liquid of the mixture and thereby restoring a desirable proportion of liquid to gas in such mixture.

In testimony whereof I have signed this specification in the presence of two sub- 120 scribing witnesses.

NICOLAI H. HILLER.
